UNITED STATES PATENT OFFICE.

GUSTAV EGLOFF AND HARRY P. BENNER, OF CHICAGO, ILLINOIS, ASSIGNEES TO UNIVERSAL OIL PRODUCTS COMPANY, OF CHICAGO, ILLINOIS, A CORPORATION OF SOUTH DAKOTA.

PROCESS FOR DISTILLING EMULSIFIED OILS.

Application filed August 20, 1920, Serial No. 404,903. Renewed April 24, 1928.

We have invented a simple process for the dehydration of emulsified oils having the following novel characteristics: We have found it exceedingly difficult to dehydrate certain crude oils from the Mexican, the California, and the Texas oil fields and bottom settling oils from the mid-continent crude oils. We have found that certain emulsified oils are exceedingly difficult to handle in a commercial manner due to their frothing and puking characteristics when subjected to heat in the normal manner of atmospheric distillation. The usual methods now in use, are not alone difficult, but are slow and tedious and relatively expensive to operate, due to the length of time required to dehydrate the oils. With our apparatus we have found that by surface distillation at atmospheric pressure, with a series of steam coils, that we can readily and expeditiously dehydrate badly emulsified oils of high stability. We have found that by layers of steam coils independently operated and controlled, that we can apply the amount of heat units necessary to distill out the water from the above enumerated emulsified oils in such a manner to overcome any tendency toward frothing or puking the still contents over into the rundown tanks. We have found that by distilling from the surface of the emulsified oil that we can control the rate of the distillation very readily and do not materially heat up the still contents so as to convert the water present violently or explosively into steam with its consequent puking the still content.

The objects of our invention are to dehydrate emulsified oil by means of surface distillation of said oil; we provide a process which distills an emulsified oil in surface layers by means of controllable levels of heat application; we provide a process for surface distillation of emulsified oils until the concentration of water present is of that percentage which makes it desirable to complete the distillation with the addition of external heat for the desired distillate products. We provide a novel form of process to carry out the aforementioned invention. The following covers a description of the process and apparatus as operated: Fig. 1 is a side elevation of the apparatus.

Figure 2 is a transverse sectional view through the still, and Figure 3 is a longitudinal sectional view. 1 represents the still, having steam coils, 2, 3 and 4, separately controlled by valves, 5, 6 and 7. 8 is steam pipe connection to the boiler controlled by valve, 9, attached to header, 10. Steam outlet valve, 11, controls independently heating coil, 2, from coils, 3 and 4. Valves 12, 13 and 14, control heating coils, 2, 3 and 4, independently of one another. Exhaust steam from heating coils, 2, 3 and 4, when operated independently or together passes out of the system by means of header, 14, controlled by valve, 15. Piping, 16, is a vapor line connected with condenser coil, 17, set in condenser coil box, 18. Condenser coil, 17, is connected with receiver or rundown tank, 19, by means of pipe, 20. The still, 1, is charged by means of pump (not shown) attached to pipe, 21, controlled by valve, 22. Residuum draw-off pipe, 23, having control valve, 24, and pipe connection, 25, is connected with a rundown tank (not shown in the drawing). 26 represents a furnace having bridge wall, 27, and stack, 28, connected to furnace, 26. 29 is a gas burner set in furnace, 26.

A typical mode of operation is to charge the still by means of the pump through valve, 22, until the liquid level of the emulsified oil is just on a level with heating coil, 2. Heating coil, 2, is charged with steam continuously so as to surface distill the emulsified oil in still, 1. As the distillation continues and the liquid level in the still becomes lower than the heating coil, 2, and on a level with coil, 3, steam is turned in to said heating coil, 3, so that the surface distillation of the emulsified oil continues until the level of the emulsified oil in still, 1, reaches that of the heating coil, 4, at which point steam is allowed to pass through coil 4. Dependent upon the type of emulsified oils, it may be desirable to cut out the heating coil, 2, when the liquid level reaches below said coil, and likewise cut out coil, 3, when the liquid level has reached that of coil, 4. We have found that in certain emulsified oils we could materially assist the rapidity of distillation of the emulsified oils when the con-

centration of water present had reached a relatively low point, by the addition of direct heat on the bottom of still, 1. We have been unable to distill with any rapidity at all 5 emulsified oils by direct heating of the bottom of the still when the raw stock was used. We have found that some emulsified oils froth badly even though a concentration of water present had reached as low as 4 or 5 10 per cent. Hence, considerable care must be observed when the application of external heat to the still is made. However, this is a point which is dependent upon the type of starting emulsified oil and it becomes a matter 15 of experience when to assist the distillation by the application of external heating.

We claim as our invention:

1. A process for distilling emulsified mineral oils, consisting in introducing a bulk 20 supply of oil with emulsified water to a still, in applying heat directly to the surface of the oil in the still, and in progressively low-

ering the point of application of the heat in the still as the oil level therein decreases by the evaporation of the contained liquid, and 25 in finally applying external heat to the still to vaporize the oil remaining therein.

2. A process of distilling emulsified mineral oils, consisting in charging a still with a bulk supply of oil containing water in emulsion, subjecting the surface only of said emulsified oil to the action of a distilling temperature, in progressively lowering the point of application of the heat in said still in consonance with the oil level therein as 30 the liquid is evaporated until a body of liquid oil substantially free of water is provided, and in thereafter subjecting said entire body of oil to a temperature sufficient to 35 distill said oil body by the application of external heat to said still.

GUSTAV EGLOFF.
